LORA E. POOLE, OF ANDERSON, INDIANA, ASSIGNOR TO DELCO-REMY CORPORATION,
OF DAYTON, OHIO, A CORPORATION OF DELAWARE

MACHINE FOR FLUXING AND COATING ELECTRICAL CONDUCTORS

Application filed October 31, 1927. Serial No. 229,982.

This invention relates to the manufacture of armatures for dynamo electric machines and particularly to the manufacture of bar wound armatures which are used in electric 5 motors for starting internal combustion engines.

One object of the present invention is to reduce the cost of manufacturing armatures by facilitating the preparation of the 10 armature conductor leads for soldering to the bars of the commutator. In the present invention this object is carried out by a machine for fluxing the ends of the armature leads and for coating the ends of the leads 15 with another metal such as tin to facilitate soldering.

Further objects and advantages of the present invention will be apparent from the following description, reference being had 20 to the accompanying drawings wherein a preferred embodiment of one form of the present invention is clearly shown.

In the drawings:

Fig. 1 is a fragmentary front elevation of 25 a machine embodying the present invention.

Fig. 2 is a side elevation, partly in section, the section taken on line 2—2 of Fig. 1.

Fig. 3 is a longitudinal sectional view on 30 the line 3—3 of Fig. 2.

The fluxing and tinning machine comprises a fluxing apparatus and a metal coating apparatus which are co-ordinated in their operations in such a way that the operator may load and unload the apparatuses 35 with the minimum of effort.

The fluxing apparatus comprises a flux trough 20 in which a suitable flux is kept in a liquid state approximately at the level 21. 40 The trough 20 is supported by pedestals 22 upon a base 23 which is supported above the level of the floor indicated at 24 by angle iron legs 25. The pedestals 22 are provided with central bores 26 in alignment respectively with tubular guides 27 extending upwardly from and integral with the bottom of the trough 21. It will be noted that the tubular guides 27 extend above the level of the flux in order that liquid will not 45 escape through the guides. Below the

pedestals 22 the table base 23 supports a plurality of guide brackets 28 each having a guideway 29 in alignment with the tubular bore 26 of a pedestal 22 and with the tubular guide 27. Each guide bracket 28 and its companion guide 27 supports for vertical movement a plunger 30 carrying on its lower end a roller 31 which cooperates with a cam 32 carried by a shaft 33 supported beneath the base 23 by brackets 34, 35 and 36. The shaft 33 carries a sprocket wheel 37 which is driven by a sprocket chain 38 in a manner to be described later.

The fluxing apparatus shown in Fig. 1 is large enough to accommodate at one time 65 six armatures. Hence there are six guides 27 each adapted to receive the end 40 of an armature shaft 41 supporting a core 42 and conductors, only a few of which are shown at 43 for the sake of clearness. There are 70 six plungers 30 and six cams 32, and the cams are fixed upon the shaft 33 and are spaced angularly 60 degrees so that the plungers 30 will move through their cycles 75 of movement in succession and will be out of phase with each other to an amount corresponding to 60 degrees of rotation of the shaft 33. Each cam 32 is shaped so that during about 45° of its movement the armature conductors 43 will be descending 80 below the level 21 of the flux; during about the next 45° the leads 43 will remain at rest, and during the next 45° the leads will ascend and during the next 225° the armature shaft will be held in uppermost position.

The tinning apparatus is constructed in a manner similar to the construction of the fluxing apparatus and comprises a trough 50 for containing a molten metal, the level of 90 which is indicated at 51. The trough 50 is supported upon tubular pedestals 52, each having a central bore 53 in alignment with a tubular guide 54, the upper end of which terminates above the level of the molten metal indicated at 51. Below the table 23, the table supports a plurality of guide brackets 55, each having a guide 56 in alignment with the pedestal 53 and the guide 54. Each guide bracket 55 and its companion guide 54 sup-

ports for vertical movement a plunger 57 carrying at its lower end a roller 58 adapted to engage a cam 59 driven by a shaft 60.

The tinning apparatus will accommodate at one time as many armatures as the fluxing apparatus for example, six armatures as shown in the drawings. Hence, there will be six tubular guides 54 extending from the bottom of the trough 50 for receiving respectively at one time six armature shafts 41, and there are six plungers 57 operated respectively by six cams 59 which are secured to the shaft 60 in such a way that the plungers 57 will perform their cycles of operation in succession and will be out of phase with each other by an amount corresponding to 60 degrees of rotation of the shaft 60. Each cam 59 is shaped so that during about 67½° of rotation, it will lower the plunger 26 and hence the armature leads 43 into the tin bath, during the next 180° the leads will remain stationary in the bath, during the next 67½° the leads will be elevated from the bath, and during the next 45° the armature will 25 be maintained in uppermost position.

The shaft 60 is driven by an electric motor 70 through a belt or chain drive including pulley 71, belt 72 and pulley 73, and through a train of worm gears 74 and 75, the gear 74 being driven by a shaft 76 carrying the pulley 73, and the worm gear 75 being attached to the shaft 60. The shaft 33 is driven at the same speed as the shaft 60 by a sprocket wheel 77 which drives the chain 38 for driving a sprocket wheel 37 on the shaft 33. The time relation between the shafts 60 and 33 is such that when the plunger roller 31 on the extreme right hand of Fig. 1 is uppermost, the plunger 57 on the extreme right of Fig. 3 will be uppermost. The result of this arrangement can be explained more clearly by numbering the armatures from 1 to 6 inclusive beginning at the left hand side so that the shafts 45 of the armatures in the fluxing device will bear the numbers 41-1; 41-2; 41-3; 41-4; 41-5; 41-6. The various armature shafts in the tinning apparatus are numbered 41-1a; 41-2a; 41-3a; 41-4a; 41-5a; and 41-6a. Assume that the shaft number 41-6 has gone through a cycle of movements in the fluxing apparatus and has reached the uppermost position while the other five shafts are at lower elevations and are gradually ascending to the uppermost position; and also that the shaft 41-6a in the tinning apparatus has reached its uppermost position after having gone through a cycle of movements to immerse its armature leads in the tin bath and withdraw them from the tin bath, and that the other five armature shafts numbered 41-1a; 41-2a; 41-3a; 41-4a and 41-5a are at lower elevations but are approaching their uppermost positions. This 60 status of the machine will indicate to the

operator that the leads of shaft 41-6 have been sufficiently fluxed to receive a coating of tin and that the leads of shaft 41-6a are coated with tin or other metal for facilitating soldering. The operator will remove the shaft 41-6a and its armature with one hand and replace it with the shaft 41-6 having fluxed but untinned leads, the placing of the shaft 41-6 being performed with the other hand. Following this operation the 70 operator will place within the empty guide 75 another shaft carrying unfluxed leads.

During the time in which the operator removes the tin work piece from the tinning device and replaces it with an untinned one 80 removed from the directly adjacent fluxing device, and then places an unfluxed work piece in the fluxing device, the shafts 41-5 and 41-5a will have arrived at the uppermost position while all the other shafts are lower. 85 The operator will then know that he is to repeat these operations with respect to shafts 41-5a and 41-5 with an unfluxed assembly. These manipulations will then be repeated in the same manner with respect to 90 the shaft assemblies located at 41-4a and 41-4; then with respect to the shaft assemblies 41-3a and 41-3; and so on down the line moving from right to left until the last pair of assemblies 41-1a and 41-1 are 95 reached and are manipulated as described. Then the operator will move opposite the assemblies 41-6a and 41-6 which meanwhile have been lowered into the tin and flux baths respectively and have been again elevated to positions higher than any other in the tin and flux baths respectively. 100

Each cam 32 has been constructed so that the armature leads will be submerged in the flux bath sufficiently to cleanse the leads from 105 oxides and each cam maintains the shaft 41 in uppermost position for a time sufficient to permit the excess flux to drain from the leads.

Each cam 59 is so constructed that it will 110 permit the shaft 41 to remain in lowermost position for a time sufficient for coating the leads with metal, but no longer than is necessary so that the leads will not soak up an excess of coating metal, or being dissolved 115 in it.

A single operator is all that is required for manipulating the entire machine. He may keep six armatures in process at one time in the flux bath and six armatures in the tin 120 bath and yet have time to remove the armatures and replace them by others in the manner already described.

The means for heating the metal trough 50 has not been disclosed, but it will be understood that any suitable heating means may be located within a furnace chamber 80 which surrounds the trough 50. The chamber 80 is enclosed by a refractory side wall 81 and 125 bottom wall 83 and a heavy cast metal 130

cover plate 84 having an opening 85 through which the interior of the trough 50 is accessible.

While the form of embodiment of the present invention, as herein disclosed, constitutes a preferred form, it is to be understood that other forms might be adopted, all coming within the scope of the claims which follow.

What is claimed is as follows:

1. A machine for treating armature conductor leads preparatory to attaching them to a commutator, comprising in combination, a trough for containing a liquid, means for receiving the lower end of an armature shaft and for vertically guiding the same, said armature shaft carrying the armature conductors with the leads thereof extending downwardly, and means for supporting the armature shaft upon its lower end and for causing the shaft to move vertically.

2. A machine according to claim 1 in which the armature shaft guide is a tubular member which extends upwardly from the bottom of the trough and terminates above the level of the liquid in the trough, and a rod extends through the bottom of the trough and into the guide, and a rotatable cam located below the trough operates the rod.

3. A machine according to claim 1 having a plurality of tubular guides each adapted to guide an armature shaft for vertical movement and each receiving a vertically movable rod for supporting an armature shaft, an operating shaft, and a plurality of similar cams attached to the shaft and each operating a rod, the cams being so located upon the shaft that the rods will rise to the uppermost elevation in succession.

4. A machine for fluxing and metal-coating the armature leads of an armature comprising, in combination, an elongated trough for containing a liquid flux, an elongated trough for containing a molten metal, the second trough being located parallel to the first and at a higher elevation, a plurality of tubular guides arranged in a row in each trough and extending upwardly from the bottom of each trough, each guide receiving an armature shaft supporting conductors with their leads extending downwardly, two rows of vertically movable rods received by the rows of guides respectively, power-operated, parallel shafts mechanically connected to operate at the same speed, each shaft carrying cams for operating respectively the rods of one of the rows of rods, the cams of each shaft being so located that the rods will rise to the uppermost elevation in succession, and so that an armature in a certain position adjacent the flux bath will be elevated simultaneously with the elevation of an armature in a corresponding position in the metal-coating bath.

5. A machine for metal-coating the armature leads of an armature, comprising in combination, an elongated trough for containing

molten metal, a plurality of tubular guides arranged in a row in the trough and extending upwardly from the bottom of the trough, each guide receiving an armature shaft supporting conductors with their leads extending downwardly, a row of vertical movable rods received by the row of guides, the upper end of each rod being engageable with the lower end of an armature shaft, a power operated shaft, carried by said shaft for operating the rods in the row, the cams being so located that the rods will rise to the uppermost elevation in succession.

6. A machine for fluxing and metal-coating the armature leads of an armature, comprising in combination, a trough for containing a liquid flux, a trough for containing a molten metal, the second trough being located adjacent to the first and at a higher elevation, a plurality of tubular guides arranged

in each trough and extending upwardly from the bottom of each trough, each guide receiving an armature shaft supporting conductors with their leads extending downwardly, vertically movable rods received by the tubular guides, cam means for operating respectively the rods received by the guides in one trough

so that the rods will rise to the uppermost elevation in succession, and cam means for operating the rods in the guides of the other trough so that the rods will rise to the uppermost elevation in succession and so that the armature in a certain position adjacent the flux bath will be elevated simultaneously with the elevation of the armature in the corresponding position in the metal bath.

7. A machine for fluxing and metal-coating the armature leads of an armature, comprising in combination, a trough for containing a liquid flux, a trough for containing a molten metal, the second trough being located adjacent to the first, a tubular guide in each trough and extending upwardly from the bottom of each trough, each guide receiving an armature shaft supporting conductors with their leads extending downwardly, two vertically movable rods received by the guides respectively,

power operated shafts mechanically connected to operate at the same speed, each shaft carrying a cam for operating the rods so that the armature in the flux bath will be elevated simultaneously with the elevation of the armature in the metal-coating bath.

8. A machine for coating the armature leads of an armature, comprising in combination, a trough for containing a liquid, a tubular guide arranged in the trough and extending upwardly from the bottom of the trough, the guide receiving an armature shaft supporting conductors with their leads extending downwardly, a tubular pedestal supporting said trough and aligned with the tubular guide, a movable rod received by the guide and pedestal and power means so constructed and arranged as to raise the rods to the upper-

most elevation whereby said armature leads are raised from the liquid.

9. In a machine for coating the armature leads of an armature comprising, the combination of a trough containing a liquid, with a tubular guide extending upwardly from the bottom of the trough, the upper end of said guide terminating above the level of the liquid, the guide supporting an armature shaft supporting conductors with their leads downwardly, and means operating in said guide for causing the shaft to move vertically in the guide.

10. In a machine for treating the armature leads of an armature comprising, the combination of a trough for containing a liquid, with a plurality of tubular guides extending upwardly from the bottom of the trough, the upper end of said guides terminating above the level of the liquid, each of the guides supporting an armature shaft supporting conductors with their ends downwardly, a plurality of devices each operating in a guide for causing a shaft to move vertically in a guide, and power operated means for operating said devices in succession.

11. A machine for fluxing and metal coating the armature leads of an armature, comprising in combination, a trough for containing a liquid flux, a trough containing molten metal, the second trough being located adjacent to the first trough, a plurality of tubular guides extending upwardly from the bottom of each trough, the upper end of said guides terminating above the level of the liquid contents in the trough, each guide receiving an armature shaft supporting conductors with their leads extending downwardly, a plurality of devices each operating in a guide for causing a shaft to move vertically in a guide, and power operated means associated with the shaft moving devices of each trough for causing said devices to operate in succession.

12. A machine for coating armature conductor leads, comprising in combination, a vessel for containing a coating material, a plurality of sockets within the vessel and terminating above the level of coating material each socket being adapted to receive the lower end portion of an armature shaft which supports conductors the leads of which extend downwardly into the vessel, and devices for causing the shafts to move concurrently and to arrive at lowest and uppermost positions in succession.

In testimony whereof I hereto affix my signature.

LORA E. POOLE.
